UNITED STATES PATENT OFFICE.

LOUIS J. RISSLING AND JOHN C. RISSLING, OF CHICAGO, ILLINOIS.

WATER-HEATING APPARATUS.

1,035,236.

Specification of Letters Patent. Patented Aug. 13, 1912.

Application filed October 28, 1911. Serial No. 657,325.

To all whom it may concern:

Be it known that we, LOUIS J. RISSLING and JOHN C. RISSLING, citizens of the United States, and residents of the city of Chicago, county of Cook, and State of Illinois, have invented certain new and useful Improvements in Water-Heating Apparatus, of which the following is a specification.

Our invention relates to improvements in water-heating apparatus and has for its object the production of a heating apparatus especially designed for domestic use, as in the kitchen.

A further object is the production of a heating apparatus as mentioned, which will be of durable and economical construction, one in which water may be heated economically and with great expedition and one which will be of high efficiency in operation.

Other objects will appear hereinafter.

With these objects in view, our invention consists in the combination and arrangement of parts hereinafter described and claimed.

Our invention will be more readily understood by reference to the accompanying drawing forming a part of this specification and in which,

Figure 1 is a central vertical section of a water-heating apparatus embodying our invention, and Figs. 2 and 3 are transverse sections taken on line *x-x* and *y-y* respectively of Fig. 1.

The preferred form of construction as illustrated in the drawing comprises a base or supporting member, which consists of legs 1, adapted to contact with the ground or floor, the upper ends of said legs being rigidly connected by a ring 2, said ring projecting slightly above the upper ends of the legs 1 for a purpose which will be hereinafter set forth. Mounted upon said base member and more precisely upon the inwardly projecting upper ends of the legs 1 is a cylinder 3, which is closed at both ends to adapt the same for the reception of water. Traversing the interior of the cylinder 3 is a plurality of longitudinally extending fire tubes 4, the latter opening and being rigidly secured in the respective heads of said cylinder as clearly shown in Fig. 1.

Surrounding the cylinder 3 is a cylindrical or tubular casing 5 which is open at both ends, the lower end of said casing fitting within the upper end of a ring 2 and being supported upon the inwardly projecting ends of the legs 1. The casing 5 is of a

diameter slightly greater than the cylinder 3 so that an annular space will be formed around the lateral wall of the cylinder 3 for the passage of heated gases or products of combustion as will be hereinafter set forth. Arranged above the casing 5 is a second cylinder 6, the lower end thereof being fitted snugly within the upper end of said casing and supported upon angular brackets 7 secured upon the inner side of said casing. The casing 5 is of a height greater than the cylinder 3, so that a chamber 8 will be formed intermediate the adjacent heads of the cylinders 3 and 6.

The interiors of the cylinders 3 and 6 communicate with each other through pipes 9 and 10, the upper end of pipe 9 being secured in the lower head of cylinder 6, the lower end of said pipe 9 passing through the upper head of the cylinder 3, and terminating within the latter adjacent the lower end thereof. The pipe 10 is secured at its lower extremity in the upper head of the cylinder 3, the upper end of said pipe, passing through the lower head of cylinder 6 and terminating within the latter adjacent the upper end thereof. Unions 11 are preferably interposed in the pipes 9 and 10 in order to afford adjustment in assembling of parts of the apparatus.

Arranged with the cylinder 6 is a plurality of longitudinally extending fire tubes 12, the lower ends of said tubes being secured in the lower head of said cylinder so as to open into the space 8 intervening the adjacent ends of the cylinders 3 and 6. The upper extremities of the tubes 12 communicate with a hollow disk 13 arranged within the upper end of the cylinder 6, the upper side of said disk communicating with outside atmosphere through a tube 14 which opens, as shown in the upper head of said cylinder.

Water is supplied to the cylinder 6 through the inlet pipe 15 which passes through the upper head of said cylinder and through the interior of the latter terminating therein adjacent the lower extremity of said cylinder. The outlet pipe 16 is secured in the upper head of the cylinder 6 so as to communicate with the upper end of the latter.

In the operation of the apparatus the water will be supplied as above mentioned through the pipe 15. A portion of the water thus supplied will drain from said

2
 cylinder through the pipe 9 into the cylinder 3. A suitable heating element such as a gas burner 17 will be arranged under the cylinder 3. Heated gases and products of combustion arising from the heating element 17 will ascend the fire tubes 4, and the annular passage surrounding the cylinder 3 and enter the space 8 intervening the cylinders 3 and 6. From the space 8 the gases will ascend the fire tubes 12, entering the hollow member 13 whence the same will be discharged through the tube 14, the gases and products of combustion thus directed effecting the heating of the walls with which the same come in contact. The lower head of the cylinder 3 will perhaps be more intensely heated being in close proximity with the flame at the heating element. Also it will be observed that the entire outer surface of the cylinder 3 will be exposed to the action of the heated gases and products of combustion, so that the water contained therein will be heated with great expedition. The gases entering the space 8 will effect the heating of the portions of the pipes 9 and 10 traversing said space and also the effectual heating of the lower head of the cylinder 6 upon which said gases and products will impinge, the pipes 12 and 14 and the member 13 utilizing practically all of the remaining heat of the gases before discharge thereof; this practically complete utilization of the heat generated at the heating element conducing to economy. By reason of the disposition of the heat in the cylinders 3 and 6 and also by reason of the peculiar arrangement of the pipes 15, 9 and 10, and 16 the circulation from the cylinder 6 downwardly through the pipe 9 into the cylinder 3 and upwardly through the pipe 10 will be effected, the water being finally discharged through the pipe 16. The device is durable and economical in construction and is not susceptible to readily becoming inoperative. Screw plugs 18 are provided in the cylinder 3 and casing 5 which may be removed if desired for the connection of the apparatus with a stove, furnace or other similar element for heating, the element 17, when this is done being dispensed with.

While we have illustrated and described the preferred form of construction for carrying our invention into effect, this is capable of variation and modification without departing from the spirit of the invention. We therefore do not wish to be limited to the exact details of construction set forth, but desire to avail ourselves of such variations and modifications as come within the scope of the appended claims.

Having described our invention what we claim as new and desire to secure by Letters Patent is:

65 1. A water-heating apparatus comprising

upper and lower superposed water chambers arranged with a space between them; a pipe leading from the lower portion of the upper chamber into the lower portion of the lower chamber; a pipe leading from the upper portion of the lower chamber into the upper portion of the upper chamber; fire tubes extending through said chambers; means for supplying water to the lower portion of said upper chamber; means for withdrawing water from the upper portion of the upper chamber; and a heating element under the lower chamber, substantially as described.

2. A water-heating apparatus comprising upper and lower superposed water chambers arranged with a space between them; a pipe leading from the lower portion of the upper chamber into the lower portion of the lower chamber; a pipe leading from the upper portion of the lower chamber into the upper portion of the upper chamber; fire tubes extending through said chambers; a water supply pipe leading into the upper portion of the upper chamber and extending downwardly therein to the lower portion thereof, said pipe being substantially in alignment with the pipe leading from the lower portion of the upper chamber into the lower portion of the lower chamber; means for withdrawing water from the upper portion of the upper chamber, said withdrawing means being arranged substantially in alignment with the pipe leading from the upper portion of the lower chamber into the upper portion of the upper chamber; and a heating element under the lower chamber, substantially as described.

3. A water-heating apparatus comprising upper and lower superposed water chambers arranged with a space between them, the lower chamber being comparatively short and the upper chamber comparatively tall and said chambers being in open communication with each other; fire tubes extending through said chambers; and a heating element under said lower chamber substantially as described.

4. A water-heating apparatus, comprising a base; a cylinder mounted on said base; a tubular casing surrounding said cylinder; a second cylinder mounted upon the upper end of said casing, there being a space intervening the adjacent ends of said cylinders; pipes connecting said ends of said cylinders and establishing communication between the interiors of said cylinders; and fire tubes extending through said cylinders and opening in the respective heads, thereof, substantially as described.

5. A water-heating apparatus, comprising a base; a cylinder mounted on said base; a tubular casing, also mounted on said base and surrounding said cylinder; a second cylinder supported upon the upper end of said

casing, there being a space intervening the adjacent ends of said cylinders; pipes connecting said ends of said cylinders and establishing communication between the interiors of said cylinders; fire tubes extending through said cylinders and opening in the respective heads thereof; and water inlet and outlet pipes communicating with the interior of said upper cylinder, substantially as described.

6. A water-heating apparatus, comprising a base; a cylinder mounted on said base; a tubular casing also mounted on said base surrounding said cylinder, said casing being 15 of a diameter slightly greater than said cylinder, so as to form an annular space around said cylinder; a second cylinder having its lower end fitted within and supported upon the upper end of said casing, there being 20 a space intervening the adjacent ends of said cylinder; pipes traversing said space and establishing communication between said ends of said cylinders; fire tubes extending longitudinally through said cylinders and opening 25 in the respective heads thereof; and water inlet and outlet pipes communicating with said upper cylinder; substantially as described.

7. A water-heating apparatus, comprising 30 upper and lower co-axial cylinders for the reception of water, said cylinders being arranged in vertically spaced relation; a pipe having its upper end communicating with the lower end of said upper cylinder; and 35 passing downwardly through the upper end of said lower cylinder, the lower end of said pipe terminating within the said lower cylinder, adjacent the lower end thereof; a second pipe having its lower end communicat-

ing with the upper end of said lower cylinder and passing upwardly through the lower end of said upper cylinder, the upper of said last mentioned pipe terminating within said upper cylinder adjacent the upper end thereof; a water inlet pipe communicating with the lower end of said upper cylinder; a water outlet pipe communicating with the upper end of said cylinder; and fire tubes passing through said cylinders and opening in the respective heads thereof, substantially as described.

8. A water-heating apparatus, comprising upper and lower co-axial cylinders for the reception of water, said cylinders being arranged in vertically spaced relation; pipes 55 establishing communication between the adjacent ends of said cylinders; a plurality of fire tubes extending longitudinally through said lower cylinder and opening in the respective heads of said cylinder; a plurality of fire tubes extending longitudinally through said upper cylinder, the lower ends of said tubes opening in the lower head of said upper cylinder; a hollow member arranged within said upper cylinder connecting with the upper ends of said last mentioned fire tubes; and a fire tube passing from said hollow member and opening in the upper head of said upper cylinder, substantially as described.

In testimony whereof we have signed our names to this specification in the presence of two subscribing witnesses.
